UNITED STATES PATENT OFFICE.

THERON P. CHASE AND ARTEMAS WARD, JR., OF DETROIT, MICHIGAN.

DESIGN FOR AN AUTOMOBILE-BODY.

51,632.

Specification for Design.

Patented Jan. 1, 1918.

Application filed April 16, 1917. Serial No. 162,576. Term of patent 3½ years.

To all whom it may concern:

Be it known that we, **THERON P. CHASE** and **ARTEMAS WARD, Jr.**, citizens of the United States, residing at Detroit, in the county of Wayne and State of Michigan, have invented a new, original, and ornamental Design for an Automobile-Body, of which the following is a specification, reference being had to the accompanying drawing, forming part thereof.

Figure 1 is a side elevation of the automobile body;

Fig. 2 is a plan of the same, and
Fig. 3 is a perspective view of the front seat showing the cowl.

We claim:—

The ornamental design for an automobile body, as shown.

THERON P. CHASE.
ARTEMAS WARD, JR.
